UNITED STATES PATENT OFFICE.

JOHN C. SMITH, OF MASSAPEAG, CONNECTICUT.

VEHICLE-WHEEL.

SPECIFICATION forming part of Letters Patent No. 660,401, dated October 23, 1900.

Application filed August 6, 1900. Serial No. 26,066. (No model.)

To all whom it may concern:

Be it known that I, JOHN C. SMITH, a citizen of the United States, residing at Massapeag, in the county of New London and State 5 of Connecticut, have invented certain new and useful Improvements in Vehicle-Wheels; and I do hereby declare the following to be a full, clear, and exact description of the invention, such as will enable others skilled in 10 the art to which it appertains to make and use the same.

This invention aims to provide a hub for vehicle-wheels, pulleys, and kindred structures comprising a rim, hub, and spokes, the 15 purpose being to devise a simple and effective construction of hub which will admit of shrinkage or looseness of any nature between the spokes and rim being easily and quickly taken up without throwing the wheel out of 20 true and which will admit of a broken or disabled spoke being replaced without loosening or detaching the remaining spokes from the rim.

The invention resides in the peculiar formation of the hub, which is divided in the 25 plane of the spokes and has the sections connected by a screw-thread joint, a spreader of conical form located between the inner ends 30 of the hub-sections and preferably attached to and constituting a part of one of said sections, and a spoke-annulus composed of sections and capable of expansion by means of the aforesaid spreader to move the spokes outward and take up any play or looseness.

For a full description of the invention and 35 the merits thereof, and also to acquire a knowledge of the details of construction of the means for effecting the result, reference is to be had to the appended description and the 40 drawings hereto attached.

While the essential and characteristic features of the invention are necessarily susceptible of modification, still the preferred embodiment of the invention is illustrated in the 45 accompanying drawings, in which—

Figure 1 is a central longitudinal section of a hub constructed in accordance with and embodying the vital features of this invention. Figs. 2 and 3 are perspective views of the 50 hub-sections. Fig. 4 is a perspective view of the spoke-annulus. Fig. 5 is a detail view in

perspective of a segment-section of the spoke-annulus.

Corresponding and like parts are referred to in the following description and indicated 55 in all the views of the drawings by the same reference characters.

The hub comprises an outer section 1 and an inner section 2, the two sections being connected by a screw-thread joint. The sections 60 are of similar construction and comprise a box portion and a wooden sleeve securely fitted upon the box portion. The box portions 3 of the hub-sections are formed at their inner ends with flanges 4, against which the wooden 65 sleeves 5 are fitted, and between these flanges is clamped the spoke-annulus. The conical spreader 6 is located in the plane of the spokes and spoke-annulus and projects across the space formed between the flanges 4 and 70 is by preference an integral part of one of the box portions and is internally threaded to receive the exteriorly-threaded tubular extension 7 of the box of the inner section 2. The tubular section 7 forms a continuation 75 of the inner box portion and serves, in conjunction with the conical spreader, to connect the hub-sections in a simple and effective manner.

The spoke-annulus is composed of rings 80 involving a sectional construction, said rings being composed of segment-sections 8, the sections 8 of one ring being disposed to break joint with the sections of the other ring. The inner edge or wall of the spoke-annulus 85 tapers in conformity to the outer wall of the spreader 6, so that when the spreader is forced into the annulus the latter is expanded and causes the spokes to move outward and take up any looseness existing between them and 90 the hub and rim. The segment-sections 8 consist of a plate 9 and wedge-shaped lugs or projections 10, spaced apart a distance corresponding to the thickness of the spoke-tenons. The sections 8 are arranged with the plates 9 95 outermost and the lugs or projections 10 facing inward. The spaces formed between adjacent lugs or projections 10 constitute sockets for the tenons of the spokes when the sections 8 are properly assembled to form the 100 spoke-annulus. For the sake of lightness and cheapness of construction the lugs or pro-

jections 10 are cored, whereby a minimum amount of metal is used in the formation of the annulus.

The segment-sections 8, as well as the box 5 portions of the hub-sections, are preferably cast, although they may be formed in any desired way, and after the sections 8 are assembled to form the spoke-annulus and the latter is received between the hub-sections 10 the spokes 11 are driven home in the spoke-sockets and fitted to the rim in the usual way. The construction is such as to admit of the spokes being first fitted to the rim and the annulus subsequently fitted to the tenoned 15 ends of the spokes. In either manner of assembling the parts any looseness between the spokes and the hub and rim is taken up by screwing the sections 1 and 2 together, which results in forcing the spreader into the 20 spoke-annulus and a corresponding expansion of the latter, so as to move the spokes outward. When all looseness is taken up and the parts firmly clamped, loosening is prevented by having the screw-thread connection 25 formed so as to tighten by turning the parts of the hub in the direction of rotation of the wheel, pulley, or the like. This necessitates uniting some of the hub-sections by a right-hand screw-thread and others by 30 a left-hand screw-thread, according to the relative position of the wheel upon the wagon or other vehicle. Should it become necessary to replace a broken or disabled spoke, the hub-sections are separated to admit of 35 access to the spoke-annulus, and sections thereof receiving the crippled spoke are removed, so as to admit of the broken spoke being displaced and substituted by a new

after the parts are reassembled, as will be readily comprehended.

Having thus described the invention, what is claimed as new is—

1. In a wheel or the like, a sectional hub, means for connecting the parts of the hub, a conical spreader in the plane of the spokes, 45 and a spoke - annulus composed of rings formed of segment-sections disposed to break joint, each segment-section being composed of a plate and spaced wedge-shaped lugs or projections, the segment-sections of the rings 50 being disposed with the plates outermost and the lugs or projections facing inward and the spaces between the said lugs unitedly forming sockets to receive the tenons of the spokes, substantially as set forth.

2. The herein-described hub composed of similarly-formed sections, each consisting of a box portion having a flange at its inner end and a wooden sleeve fitted upon its outer end portion, an exteriorly - threaded tubular extension at the inner end of one box portion, and a conical spreader at the inner end of the other box portion and interiorly threaded to receive the exteriorly - threaded tubular extension, and a sectional spoke - annulus 65 adapted to be clamped between the flanges of the box portions of the hub-sections and to be expanded by the aforementioned conical spreader, as and for the purpose set forth.

In testimony whereof I affix my signature 70 in presence of two witnesses.

JOHN C. SMITH. [L.S.]
